UNITED STATES PATENT OFFICE

ROSE WIESNER, OF JAMAICA, NEW YORK

DESIGN FOR A SLIPPER

Application filed November 3, 1930. Serial No. 37,514. Term of patent 7 years.

To all whom it may concern:

Be it known that I, ROSE WIESNER, a citizen of the United States, residing at Jamaica, L. I., in the county of Queens and State of New York, have invented a new, original, and ornamental Design for a Slipper, of which the following is a specification, reference being had to the accompanying drawings, forming part thereof.

Fig. 1 is a perspective view of a slipper, showing my new design.

Fig. 2 is an enlarged detailed elevational view of the tongue attachment shown in Fig. 1.

The novel feature in this invention resides in the ornamental effect produced by the particular contour of the tongue attachment of the slipper combined with the representation of an eye having a movable pupil therein.

I claim:

The ornamental design for a slipper, as shown and described.

In testimony whereof I have affixed my signature.

ROSE WIESNER.
